SERVICE PLATFORM LADDER

Commodore V. Wood, Sr., 1715 Tyler St.,
Amarillo, Tex.

Filed Oct. 17, 1967, Ser. No. 9,030

Term of patent 14 years

(Cl. D15—8)

FIG. 1

FIG. 2

FIG. 3

FIG. 4

FIG. 5

FIGURE 1 is a perspective view of a service platform ladder showing my design;

FIGURE 2 is a top view;

FIGURE 3 is an elevational view of one of the two identical sides;

FIGURE 4 is a front elevational view; and

FIGURE 5 is a view of the service platform ladder in substantially collapsed position.

I claim:

The ornamental design for a service platform ladder, substantially as shown and described.
